Application May 17, 1950, Serial No. 162,492

7 Claims. (Cl. 200—115.5)

1

This invention relates to thermoresponsive snap switch devices and more particularly to circuit breakers using thermoresponsive snap springs as the sensing and actuating components therein.

In the design of circuit breakers it is often difficult to achieve specific current rating and electrical contact pressure characteristics without exceeding reasonable manufacturing costs. Particularly is this true in circuit breakers of the auxiliary type such as might be used in the individual feeder lines to each piece of electrical equipment among a group, these auxiliary breakers being useful in preventing a shutdown of an entire plant when a single piece of equipment is at fault.

It is, therefore, an object of this invention to provide a circuit breaker which may be manufactured economically notwithstanding precise standards in the operating characteristics.

A further object of this invention is to provide a circuit breaker comprising a novel assembly of components which afford trip-free operation in which reclosing of the electrical circuit is effected subsequent to and not during resetting action.

To achieve the above and other objects according to the invention, a bimetallic snap spring disc adapted to snap between two configurations and carrying electrical contacts is fitted loosely on a movable carrier, and a second spring element such as a monometallic spring disc for example, is reacted between a stationary abutment and the snap disc to urge the latter against the carrier, thereby to provide a loose coupling assembly which is highly effective as well as economical. In order to prevent the snap disc from rotating on the carrier, the electrical contacts or other suitable radial extensions are provided which protrude beyond the rim of the disc to be received in suitable elongated guide channels formed in the housing. Resetting is accomplished by displacing the snap disc in translational movement in order that the snap disc may be forced onto its initial configuration without concurrently closing the electrical circuit through the circuit breaker, the latter step being performed in a separate and subsequent operation.

For a better understanding of the above and other features and advantages reference may be had to the following specification of representative embodiments of the invention taken in conjunction with the accompanying drawings, in which

Fig. 1 is a side view in cross section of a circuit

2

breaker assembly embodying the present invention taken on the line 1—1 of Fig. 2 looking in the direction of the arrows;

Fig. 2 is a view in horizontal cross section taken on the line 2—2 of Fig. 1 looking in the direction of the arrows;

Fig. 3 is a side view in cross section similar to Fig. 1 showing the circuit breaker mechanism in tripped position;

10 Fig. 4 is a side view in cross section showing the circuit breaker mechanism subsequent to the first step in the resetting operation;

Fig. 5 is a bottom view in an electrical plug or cord cap having the novel circuit breaker mechanism incorporated therein;

Fig. 6 is a view in longitudinal cross section taken on the line 6—6 of Fig. 5 looking in the direction of the arrows;

20 Fig. 7 is a view in longitudinal cross section of a modified form of the circuit breaker adaptable for installation on a panel board taken on the line 7—7 of Fig. 8 looking in the direction of the arrows, and

Fig. 8 is a side view in cross section of the unit shown in Fig. 7 taken on the line 8—8 looking in the direction of the arrows.

Referring to Figs. 1 and 2 of the drawing, the invention will be seen as embodied in a circuit breaker unit comprising an insulating lower housing portion 10 having a cylindrical recess 10a formed therein and an upper annular cap portion 11 also formed of insulating material and affixed to the lower portion by suitable means such as screws 9.

35 The cap portion 11 defines a cylindrical opening 11a of substantially the same diameter as the cylindrical recess 10a and is internally formed with an annular shoulder 12 defining an opening 12a of smaller diameter than the recess 10a.

40 The lower housing portion 10 is formed with a central bore 13 into which is threaded a bushing 14 which in turn slidably receives a push-shaft or carrier 15. The push-shaft 15 is formed adjacent its inner end with a shoulder stop 16 which 45 engages the inner end of the bushing 14 to determine the outermost position of the push-shaft.

A dished bimetallic snap spring disc 17 of slightly smaller diameter than the recess 10a is mounted within the housing to partake of peripheral snap movement, the mounting being effected by means of a central aperture formed in the disc which loosely receives the inner end of the push-shaft 15. The snap spring disc 17 is urged against the stop shoulder 16 by a dished spring disc 18 which is also centrally apertured

to receive the inner end of the push-shaft 15, the spring disc being reacted between the center portion of the snap spring disc 17 and the annular shoulder 12 formed on the housing. Normally part of the spring force of the spring disc 18 is carried by the snap spring disc 17 through peripheral contact pressure as described later, and the remainder is carried directly by the housing through the engagement of the shoulder 16 with the stationary bushing 14. Preferably an insulating spacer washer 19 is fitted on the push-shaft 15 between the discs 17 and 18 to reduce heat loss by conduction between the discs. It will be seen, therefore, that spring disc 18 and bimetallic snap spring disc 17 are loosely received on the push-shaft 15 with the assembly being maintained only by the spring force of the spring disc 18 as described.

The bimetallic snap spring disc 17 is so constructed that it will snap from its first configuration of equilibrium as shown in Fig. 1 to a second configuration as shown in Fig. 3 under the influence of heat which, in the illustrated embodiment of the invention, is developed by current flowing directly through the disc. For a more detailed disclosure of the characteristics, structure and methods of manufacture of bimetallic snap spring discs and monometallic spring discs of the types contemplated for use in the illustrated embodiments of the invention, reference may be had to the following U. S. patent applications: Serial No. 628,447 filed November 14, 1945, entitled Toggle Springs; Serial No. 635,956 filed December 19, 1945, entitled Snap Disc Springs and Serial No. 139,182 filed January 18, 1950, entitled Snap Springs and Methods of Manufacture. In the instant embodiment of the invention the snap spring disc 17 is preferably so formed that it will snap from its first to its second configuration at a given temperature as induced by a current flow therethrough, but will not return to the first configuration within the ambient temperature range in which the device is to be operated, thus necessitating a manual reset operation as described below.

A pair of electrical contact members 20 and 21 are attached to the periphery of the bimetallic snap disc 17 at diametrically opposite points as by welding or soldering to extend radially outwardly from the rim of the disc as shown. The overhanging contacts 20 and 21 are received in vertical guide channels 22 and 23 respectively, formed in the inner wall of the housing portion 16, the channels affording a guideway for movement of the contacts upon snapping of the disc between its respective configurations as shown in Figs. 1 and 3. The vertical channels 22 and 23 and overhanging contacts 20 and 21 prevent rotation of the snap spring disc 17 about the axis of the push-shaft 15, thus maintaining the proper angular orientation of the disc 17 within the housing in order that movable contacts 20 and 21 may engage a pair of stationary contacts 24 and 25 respectively, mounted at the lower extremities of the channels 22 and 23, at such times as the snap spring disc 17 is disposed in the configuration as shown in Fig. 1.

The snap spring disc 17 is formed of metal to afford an electrical path between the stationary contacts 24 and 25 and suitable conductor leads 26 and 27 extend outwardly from the stationary contacts through apertures formed in the housing to receive external wiring connections (not shown). In operation the normally closed circuit through the bimetallic snap spring disc 17

enables the latter to become heated by the passage of current therethrough. Overheating as caused by overload current induces snapping of the disc 17 to the configuration shown in Fig. 3, thereby opening the circuit and terminating the current flow in the external circuit in which the unit may be inserted. Alternatively a supplemental resistance heater may be used to afford the necessary heat to buckle the snap disc.

Resetting may be accomplished by manually forcing the push-shaft 15 inwardly against the spring disc 18, with the snap spring disc 17 being carried in axial translation until the back surfaces of the protruding contacts 20 and 21 engage the upper termini of the guide channels 22 and 23, respectively. Further displacement of the push-shaft causes the disc 17 to buckle into its initial configuration of equilibrium. In this fashion the snap disc member is manually urged into its original configuration as shown in Fig. 4 without closing the electrical circuit through the unit, the axial translation of the snap spring disc 17 having carried the movable contacts 20 and 21 for a distance exceeding the displacement afforded by the snap movement of the disc.

Releasing the push-shaft 15 enables the spring disc 18 to urge the push-shaft outwardly to carry the snap spring disc 17 in axial translation to effect reengagement of the contacts 20-24 and 21-25. Thus the push-shaft 15 acts as a reset carrier for the snap spring disc 17, the carrier being movable between first and second positions as described to effect the resetting action. Accordingly it will be seen that there is provided a duty cycle having trip-free operation in which reclosing of the electrical circuit is accomplished after and not during resetting. Thus the circuit breaker cannot be rendered inoperative, i. e. locked in circuit-closed position, by holding or clamping the push-rod 15 in its inner or resetting position.

Adjustment of the contact pressure and rating adjustment of the unit within a preestablished range may be effected by screwing the bushing 14 inwardly or outwardly as may be required. Inward movement of the bushing 14 for example, increases the current rating or trip point of the breaker and decreases the contact pressure, whereas movement of the bushing outwardly increases the contact pressure and lowers the current rating.

The invention is also shown as embodied in an electrical plug or cord cap assembly as shown in Figs. 5 and 6. In this embodiment a cup-shaped outer shell 28 receives a pair of insulating housing sections 29 and 30 which cooperate to form a cylindrical chamber for receiving the thermo-responsive disc 17, which is loosely centrally mounted on a push-shaft 31 in a manner essentially similar to that described above with reference to Figs. 1 to 4 with like components being assigned like reference numerals.

The housing portion 30 is formed with a central recess 30a into which is threaded a bushing 32 which in turn slidably receives the push-shaft 31. Fitted in the shell 28 over the housing sections 29 and 30 is a cylindrical insert member 33 made of insulating material and formed with an inner recess 33a for receiving the outer end of the push-shaft 31. The outer or exposed surface of the insert member 33 is recessed at 34 and 35 to receive a pair of conventional conductor prongs 36 and 37 which are endwise secured thereto by suitable means such as screws 38 for example.

Adjustment of the operating characteristics of the disc assembly is effected by adjusting the axial position of the bushing 32. This may be accomplished either through the screw assembly as described above or alternatively by inserting shims or spacers between the bushing and the floor of the recess 30a as may be required to adjust the axial position of the disc assembly.

Stationary contacts 39 and 40 are mounted in the housing at the lower end of the channels 22 and 23 respectively, to be engaged by the movable contacts 20 and 21 carried by the rim of the snap disc 17 when the latter is disposed in one of its two configurations.

The insert member 33 is formed with a central bore 41 which slidably receives an insulating push-button 42 affixed to a threaded extension 43 formed on the outer end of the push-shaft 31. A terminal plate 44 (Fig. 5) is formed integrally with the prong 36 and a terminal screw 44a is threaded into the plate to receive one conductor of a conventional 2-wire electrical cord (not shown). The prong 37, on the other hand, is electrically connected by conductor (not shown) to the stationary contact 40. The stationary contact 39 is electrically connected to a terminal plate 45 (Fig. 5) secured to the insert member 33 by a screw 46. A terminal screw 45a is threaded into the plate 45 to receive the second wire of a 2-wire electrical cord to which the plug is secured. Thus a circuit is provided between the terminal screw 45a and the prong 37 which includes the snap spring disc member 17 and the normally closed contacts 20-39 and 21-40.

Operation of the unit is essentially similar to that described above, with overload currents causing the snap spring disc 17 to reverse its configuration to open circuit and with resetting being accomplished by pressing inwardly on the push-button 43 to cause the snap spring disc 17 to reverse its configuration. Release of the push-button enables the spring disc 18 to return the snap spring disc 17 to circuit-closed position.

Another embodiment of the invention is shown in Figs. 7 and 8 in which the circuit-breaker assembly is incorporated in a panel board unit, the construction and operation of which is essentially similar to that described with reference to Figs. 1-4 with like components being identified by like reference characters.

Referring to Figs. 7 and 8, binding posts or conductors 48 and 49, having stationary contacts 50 and 51 formed on their respective inner ends, are brought out through openings 52 and 53 in the insulating housing portion 11. The front surface of the housing portion 10 is formed with a raised collar 54 which is formed with a central opening 54a to receive an insulating push-button 55 which is screwed on to a threaded extension 56 formed on the outer end of the push-shaft 15. Rating adjustment is effected by shifting the bushing 32 to displace the disc assembly all as described above.

It will be understood therefore that the various embodiments of the invention may be extensively modified without departing from the spirit and scope of the invention which should not accordingly be limited save as defined in the following claims.

We claim:

1. A circuit breaker assembly comprising a housing having a central cavity formed therein, a thermoresponsive snap spring disc mounted in the cavity for snap movement between two configurations, at least one contact element car-

ried by the periphery of the disc, said contact having a portion extending beyond the margin of the disc, means defining a channel in the housing for receiving a portion of the contact extending beyond the margin of the disc, cooperative stationary contact means mounted in the housing and normally engaged by said contact element when the snap spring disc is in its first configuration, and a carrier for displacing said disc in translation along the central axis of the disc and parallel to the directions of snap movement thereof, said channel being aligned with the directions of snap movement and translatory movement of the disc, whereby said contact element and channel constrain the disc against turning movement about the axis of the disc relatively to the housing.

2. In a snap switch assembly, in combination, a housing having a central cavity formed therein, a thermoresponsive snap spring disc mounted in said cavity for peripheral snap motion between two configurations, a pair of contact elements affixed to the periphery of said disc at spaced points and electrically connected thereto, said contacts each having a portion extending beyond the margin of said disc, means defining channels in said housing for receiving the radially extending portions of said contact elements, said channels permitting snap movement of said disc between its configurations and preventing turning movement about the mounting thereof, and a pair of stationary contacts mounted in the housing in cooperative relationship with the contacts carried by the disc.

3. A cord plug assembly including a housing, a plurality of terminal connectors to afford an electrical connection with a mating electrical fitting, a plurality of terminals in said housing for receiving individual conductors of an electrical cord, means providing an electrical connection between corresponding cord terminals and terminal connectors, the electrical path between at least one cord terminal and terminal connector including a thermoresponsive snap spring member mounted in said housing for control movement between first and second configurations, first electrical contact means carried by said snap spring member and corresponding second electrical contact means carried by said housing for engagement therewith to form a closed electrical path through the device when the snap spring member is in the first configuration, reset carrier means carrying said thermoresponsive snap spring member for effecting relative movement between the first and second electrical contact means and movement of the snap spring member from the second to the first configuration.

4. An electrical cord plug assembly including a housing, two or more conductor prongs extending outwardly from the housing for insertion in a plug receptacle, two or more terminals for receiving wires of an electrical cord, means affording an electrical path between corresponding prongs and terminals, at least one of said electrical paths including a bimetallic snap spring disc centrally mounted in said housing to enable its peripheral portions to partake of snap movement between two configurations, separable electrical contact means adapted to be opened during snapping of said member from its first to its second configuration to open said electrical path, and a carrier for said disc movable between first and second positions to displace said snap disc in translational movement to induce snapping of

said disc from its second to its first configuration to effect resetting.

5. A cord cap circuit breaker assembly including in combination a housing, a pair of conductor prongs extending outwardly from said housing, a pair of terminals for receiving the wires of an electrical cord, and switch means connected in series between at least one of said prongs and one of said terminals including a push-rod mounted for axial movement between first and second positions, a bimetallic snap spring disc adapted to snap between first and second configurations upon heating, said disc being centrally apertured to receive one end of said push-rod, spring means for urging said snap spring disc against the push-rod and also for urging said push-rod in the direction of its first position, a pair of spaced electrical contact elements carried by the snap disc adjacent the periphery, a pair of stationary electrical contacts adapted to be engaged by the contact elements on the snap disc to form a closed circuit therebetween including the snap disc when the disc is in its first configuration and the push-rod is in its first position, stationary abutment means in said housing adapted to be engaged by the peripheral portion of the snap disc when the snap disc is disposed in its second configuration of equilibrium and the push-rod is manually displaced in the direction of its second position, thereby to urge said disc to snap from its second to its first configuration and to maintain the engageable contacts spaced apart until said push-rod is returned to its first position.

6. A circuit breaker assembly as set forth in claim 1, said carrier for the snap spring disc comprising a post, a bushing threaded into said housing substantially coaxially of said cavity for axial adjusting movement toward and away from said disc and centrally apertured to receive slidably said post, a stop shoulder on said post disposed between the ends thereof and adapted to engage the inner end of said bushing to determine one axial position of the post, said snap spring disc being centrally apertured to receive the inner end of said post, resilient means urging the center portion of said snap spring disc toward said stop shoulder and urging said stop shoulder toward the inner end of said bushing, and abutment means on said housing and disposed at the opposite end of said contact-receiving channel from the said stationary contact element to be engaged by the snap spring disc when the latter is in its second configuration, whereby said post may be urged inwardly to cause said stop shoulder and said abutment means to

55

react against the disc to reverse the disc from its second to its first configuration, and whereby axial adjusting movement of the bushing changes the thermoresponsive trip point of said disc from the first to the second configuration.

5 7. A circuit breaker assembly comprising a housing having a cavity formed therein, a thermoresponsive snap spring member received in said cavity and adapted to snap from a first to a second configuration under the influence of heat, a normally stationary bushing threaded into said housing to enter said cavity, said bushing being adjustable axially toward and away from said cavity, a post slidably received in said 10 bushing and entering said cavity, a stop shoulder on said post within said cavity and spaced axially away from the inner end of said post, said stop shoulder being adapted to engage the inner end of the bushing to limit the outward axial sliding 15 movement of the post, said snap spring member being formed with an opening between its extremities to receive the inner end of said post, resilient means for urging said snap spring member toward said stop shoulder and for urging said post axially outwardly, electrical contact means controlled by snap action of said snap spring member between its two configurations, and abutment means on said housing adapted to be engaged by the extremities of said snap 20 spring member when the post is moved inwardly and when the snap spring member is in its second configuration, said snap spring member being adapted to be reacted between said stop shoulder and said abutment means to be reversed 25 to its first configuration, the trip point of said snap spring member from its first to its second configuration being controlled by the axial adjustment of said bushing.
